Knut Andreas Knutsen, Paris, France

Application March 19, 1937, Serial No. 131,848

9 Claims. (Cl. 101—93)

The present invention relates to a printing device particularly adapted to be used in combination with record card controlled tabulating machines.

- 5 An object of the invention is to combine the selecting means of the alphabetical printing device shown in my prior patent application, Patent Number 2,046,465, with a printing device comprising a type-carrier.
- 10 Said type-carrier comprises a number of circumferential columns in which letters or letters and ciphers are spaced on the circumference arranged in groups. When the printing device is connected to a card controlled tabulating machine, a record card controls two distinct operations of the printing device. Firstly the time that shall elapse or the angular displacement of the type-carrier during said time, from the moment when the printing operating means have been 15 coupled with the driving means, until the hammer shall hit the paper, said time being determined by the positioning of a selecting organ, secondly the moment when the printing operating means shall be coupled with the driving means.
- 20 Another object of the invention is to provide means whereby in a printing device comprising a type-carrier with letters and ciphers arranged in groups, spaced along the circumference thereof, complete selection and printing of a type may be 25 executed within one single revolution of the type-carrier.

Another object of the invention is to provide means whereby in a printing device comprising a type-carrier with letters and ciphers arranged in groups spaced on the circumference thereof, the selection of the group to which the type to be printed belongs, and the selection and printing of a type within the selected group, may be controlled from a record card by means of one single 30 magnet.

Another object of the invention is to provide means whereby in a printing device connected with a record card controlled tabulating machine, comprising a type-carrier with letters and ciphers arranged in groups and spaced on the circumference thereof, the type to be printed within each group is selected by means of a selector organ (pawl 53) and a rack which moves in relation to each other, or in timed relation to the movement 35 of the types on the type-carrier past the printing position, whereby only one single tooth of the rack passes the selector organ for each group of types on the type-drum that passes the printing position.

40 A machine embodying the present invention

will now be described, by way of example only, with reference to the accompanying drawings in which:

Fig. 1 is a vertical section through the machine, showing the type selection means and the printing mechanism. 5

Fig. 2 is a side elevation of the gear drive between the main shaft of the machine and different cam shafts, and an alternative form of execution of the gear drive between the main shaft of the machine and the shaft of the type-carrier. 10

Fig. 3 is a front view of Fig. 2.

Fig. 4 shows the normal gear drive between the main shaft of the machine and the shaft of the type-carrier. 15

Fig. 5 is a schematical plan of the tabulating machine connected with the printing device.

Fig. 6 is a vertical section through the machine showing the position of the different parts during the selection of a type belonging to group 9. 20

Fig. 7 shows a detail of the gear drive shown Fig. 2.

Fig. 8 shows the position of the parts acting on the type-hammer at the moment when this latter begins to be moved against the paper. 25

Fig. 9 is a vertical section through the machine showing the position of the different parts at the moment when the type "Z" belonging to group 9 is printed.

Fig. 10 is a schematical section of the card feeding device showing the card reading device and the diagram of the circuits connecting this device to the printing mechanism. 30

Fig. 11 is a vertical section showing the different parts in position at the moment when the type group 9 corresponding to the perforation 9 is selected. 35

Fig. 12 shows a record card with the code of perforations.

Fig. 13 is a vertical section of the type-carrier according to an alternative form of execution. 40

Fig. 15 is a front view of Fig. 14.

Fig. 16 is a horizontal section through the shaft of the type-carrier Fig. 14.

Fig. 17 shows the wiring diagram for printing the amounts contained on the totalizer wheels. 45

Fig. 18 is a cross section on line A—B, Fig. 17.

The drawings show the printing device combined with a tabulating machine controlled by perforated cards. 50

In Fig. 1, the shaft 1 is the main shaft of the printing device. On this shaft is fixed a toothed-wheel 2, which is in mesh with the intermediate toothed-wheel 3 turning on the pivot 4 fixed to the frame. The wheel 3 is in mesh with the 55

toothed-wheel 5 fixed to the shaft 6 of the type-carrier 7. For each revolution of the shaft 4, the shaft 6 and the type-carrier perform one revolution.

- 5 In Fig. 5 is shown in a schematic way the connection of the printing device to a tabulating machine. The main shaft 4 of the printing device P is common with the main shaft of the totalizers T. By a gear drive 8, 9, the shaft 4 is rotated 10 constantly by a motor M. The shaft 4 is further provided with a clutch C, controlled by a magnet 10. Normally the clutch connects the shaft 4 with the shaft 11 of the card feeding device F (shown on Fig. 10).
 15 To the shaft 11 (Fig. 10) is fixed a toothed-wheel 12 in mesh with an intermediate toothed-wheel 13 turning on the stationary pin 14. The wheel 13 is in mesh with a toothed-wheel 15 fixed to the shaft 16 on which is fixed the cam 17. The card picker lever 18 is pivoted on the pivot 20 fixed to the frame, and is pushed against the cam 17 by the spring 19. For every revolution of the shaft 4, the card picker lever 18 will introduce one single card of the pile 21, 25 in well known manner between the first pair of feeding rollers 22-23. A gear train 31, 32 connects the feeding rollers with wheel 13 in such a manner that the card will move at a determined speed in synchronism with the rotation of the 30 type-drum. The card passes a first card reading device 24, another pair of feeding rollers 25, 26, a second card reading device 27, a third pair of feeding rollers 28, 29, and comes to rest in the receptacle 30. A cam 33 comprising a disc with 35 12 toothed-formed cams, closes a contact 39, every time a place of perforation passes under the card reading device 27, and cuts off the circuit in the interval between two places of perforations, and in the interval between the cards. 40 A "card contact" 37 cuts off said circuit in known manner when no card passes under the card-reading device.

Every time a perforation in a card passes under the card-reading device 27, and this, which in 45 the present case consists of a brush has made contact through the perforation, the cam 39 closes the circuit which energizes a magnet 38. The cam 39 will cut off the circuit again, before the perforation has left the brush, and magnet 50 38 will be demagnetized, Figs. 10 and 1. When a letter is to be indicated by the perforations of a card, generally a combination of two perforations in one same column of the card is utilized. These two perforations when passing the 55 reading device of the column will each close a circuit in order to effect the printing of a letter. In the present application is utilized a system of perforation as shown on Fig. 12. The letter B for instance is represented by the two perforations 7 and 0. These two perforations are 60 both read by the same reading device 27, causing at two different times the energizing of the magnet 38 during the passage of a card. The first time, the magnet effects the selection of the 65 group to which the type to be printed belongs, the second time, it effects the selection of the type to be printed within each group. If only ciphers are to be printed, the group selecting means may be omitted or neutralized and the 70 magnet will, when energized, effect the printing of the cipher corresponding to the perforation that has been read.

For every column of the card, there is a reading device 27, a column of types spaced on the 75 circumference of the type-drum, a typehammer,

a magnet, and separate typehammer operating means.

The main shaft 4, Fig. 1, is integral with a cylinder forming a common driving ratchet 51 for the printing operating means for all the 5 circumferential columns of the types on the type-carrier. If a line of 100 letters should be printed on the paper, the type-carrier should comprise 100 circumferential columns, each comprising 26 letters and 10 ciphers, spaced on the circumference of the type-carrier. To each of said type-column corresponds a typehammer 52 operated by corresponding selecting means from the common driving ratchet 51. The driving ratchet is, on its circumference, provided with teeth, one 15 tooth for each perforation in a column of a card, which corresponds to each fourth type on the circumference of the type-carrier.

Whenever a perforation in a card is passing the card reading device 27, a tooth of the ratchet 20 51 is passing the pawl 53 of the printing operating means, and a letter of a determined group of types is passing the printing position. The type selecting means corresponding to one single column of the card will now be described.

The pawl 53 pivots on the pivot 54 fixed to the sector 55 which is provided with four steps 9, 8, 7, 6, and which is pivoted on the stationary spindle 60. The sector 55 is held in position against a stationary bar 61 pulled by the spring 30 62 fixed at the other end to the left extremity of another sector 63. Said sector 63 is pivoted on a stationary spindle 64 and forms with its inferior extremity a rack provided with 4 teeth: 9, 8, 7, 6. To the sector 63 is fixed a pin 65 on 35 which may turn a roller 66, and another pin 67 on which is pivotally connected a link 68. The spring 62 pulls the sector 63 with the roller 66 against a cam-shaped shaft 69. The link 68 is at its other end pivotally connected to the pushing lever 70 by the pin 71. To its upper extremity is fixed a spring 72 which at its other end is fixed to a plate 73 fixed to the frame. The spring 72 pulls the link 68 against the stationary spindle 74. To the pushing lever 70 is fixed a spring 75 at its other end to the plate 76 fixed to the frame. The spring 75 keeps the pushing lever 70 pulled against the stationary spindle 82. The pushing lever 70 is further provided with a tooth 77 adapted to engage with 45 the lower extremity 78 of a typehammer 52 which may swing on a stationary spindle 79. The typehammer is kept in position by the spring 80 against the stationary bar 81 fixed to the frame. The spring 80 is at its other end fixed to a plate 55 43 fixed to the frame. The pushing lever 70 is provided with an inclined edge 83 adapted to engage with the stationary spindle 82 when the pushing lever is moved to the right, in such a way that the tooth 77 will be disengaged from 60 the extremity 78 of the typehammer 52. The left extremity 84 of the pushing lever 70 is shaped to engage with one of the steps 6 to 9 of the sector 55. The lever 85 pivots about a stationary spindle 86 and is provided with a nose 87 and 65 a pin 88 carrying a roller 89. The lower extremity 90 of the lever 85 is engaged with the nose 91 of a crank lever 92 which pivots on the stationary spindle 93. The lever 85 is further provided with a spring 94 fixed to its other end 70 to the bar 95 fixed to the frame. The crank lever 92 is provided with a second nose 96 which engages with the extremity 97 of the lever 98 pivoting on a stationary spindle 99. The lever 92 is further provided with a spring 100 fixed at 75

the other end to the plate 101 fixed to the frame. The link 102 is pivotally connected to the lever 92 by the pin 103, and at its other end, by the pin 104 to the armature 105 of the magnet 38 which is fixed to the plate 106 fixed to the frame. To the lever 98 is fixed a pin 107 provided with a roller 108. To the left extremity of lever 98 is fixed a spring 109 which at its other end is fixed to the plate 110 fixed to the frame. By the pin 111 the lever 98 is pivotally connected to a link 112 which at its other end, by the pin 113 is pivotally connected to the pawl 53. The link 112 is provided with a projection 114 adapted to engage with the stud 115 fixed to the lever 116 which pivots on a stationary spindle 117. The lever 116 is further provided with a spring 118 fixed at its other end to a plate 119 fixed to the frame. The spring 118 pulls the lever 116 against the stationary spindle 120. The roller 108 on lever 98 is adapted to engage with the cam-shaped shaft 121. The roller 89 on lever 85 is adapted to engage with the cam-shaped shaft 127. The bar 128 stretches all over the machine and is adapted to engage with the lever 92 and assures the movement of this lever and the backward movement of the armature 105 when the magnet 38 has been demagnetised. The bar 128 is at each end of the machine fixed to the levers 129 each pivoting on a pivot 130 fixed to the frame. The levers 129 are on the left extremity provided with the rollers 131, each pushing against a cam 132. Each lever 129 is provided with a spring 133 fixed at its other end to the frame. The cam 132 is fixed on each side of the machine to the shaft 121 and provided with two projections 134 and 135 which cooperate with the rollers 131 and pivot the levers 129 about the pivots 130 at determined moments of the cycle of the machine. On shafts 121—127 and 69 are fixed the toothed-wheels 136, 137, 138 which, by the intermediate gears 139 and 140 are in mesh with each other. The gear 140 is further, by the intermediate toothed-wheel 141 in mesh with the toothed-wheel 2 fixed to the main shaft 1. The said wheels are so measured that the shafts 121, 127 and 69 make one revolution when the main shaft 1 makes one revolution. At a little distance of the circumference of the type-carrier 7 are fixed to the frame the guide-plates 150 and 151 which guide the paper 152 from the paper feeding rollers 153—154 until the paper reaches the printing position. After the paper has passed the printing position, it is guided by the guiding plates 155 and 156. Between the paper and the type in printing position is placed the ink-ribbon 157.

It will now be described how the perforations in a column of a card control the selection of the type to be printed, and the printing of this type on the paper. The card passes the reading device 27 in such a way that the first place of perforation of the card that passes under the reading device is the perforation 9 (Fig. 12). At this moment, the driving ratchet 51 will take the position indicated on Fig. 11. If there is a perforation at this place of the card, a circuit will be established from the battery 34, cam contact 39, card contact 37, contact plate 35, perforation of the card, brush 27, magnet 38 and back to the battery. The magnet 38 will be energized, whereby the armature 105 will swing the lever 92 in clockwise direction in such a manner that it releases the lever 85, which, by the spring 94 will be swung so that the tooth 87 engages with the tooth 9 of the sector 63. The sector 63

takes the position shown on Fig. 11, because of the timed relation of the cam shaped shaft 69 to the shaft 16 of the feeding device. The shaft 121 is further in such timed relation to shaft 69, that the lever 98 is blocked by the cam 125 in 5 the position shown Fig. 11. The blocking of the sector 63 will maintain the pushing lever 70 in the position shown Fig. 11, in which the extremity 84 will be engaged with the step 9 of the sector 55 when this sector, later in the cycle 10 will be swung in clockwise direction. The card moves further under the card reading device 27, and the other places of perforations 8, 7, 6 will pass under the brush. During the time when the places of perforations 9, 8, 7 pass under the 15 brush 27, the roller 108 is located on the cam 125, so that the lever 98 is blocked, and it is only when the place perforation 6 arrives under the brush 27 that the shaft 121 has rotated sufficiently to permit the roller 108 to drop from 20 the cam 23 as shown on Fig. 1, if there is a perforation on the place 6 on the card. Supposing this is the case, the magnet 38 will be energized a second time, and the lever 92 will again be swung in clockwise direction releasing now 25 the lever 98. The spring 132 will swing this lever in counterclockwise direction, whereby the pawl 53 will be engaged with the tooth 6 of the driving ratchet, as shown Fig. 6. By this engagement, the pawl 53 through the movement of the 30 ratchet will be forced to move to the right, urging the sector 55 to turn in clockwise direction about the spindle 60 until the step 9 of the sector 55 hits the extremity 84 of the pushing lever 70 as shown on Fig. 8. The ratchet continues to 35 turn, and the pushing lever 70 will be pushed to the right out of its initial position, until the pawl 53 will be disengaged from the driving ratchet as later explained, and as shown on Fig. 9. During the movement of the pushing lever 70 to the 40 right, the tooth 71 engages the lower extremity 78 of the typehammer 52, so that the latter will be swung violently in counter-clockwise direction and hit the paper, whereby the type now in printing position will be printed—Figs. 8 and 45 9. At this moment, the pushing lever 70 will be no longer in engagement with the typehammer, because the inclined edge 83 being pushed against the stationary spindle 82 will force the right extremity of the pushing lever 70 to move 50 downwards, whereby the tooth 71 moves out of engagement with the extremity 78 of the typehammer. At this moment, also the pawl 53 will be disengaged from the driving ratchet by means of a lever 116—Fig. 9. The link 112 is moved to 55 the right with the pawl 53 and engages with its upper part the stud 115 which is fixed to the lever 116. The lever 116 will therefore turn in clockwise direction about the spindle 117, whereby the stud 115 will be engaged with the projection 114 and force the lever 112 downwards as indicated Fig. 9. When the pawl 53 thus is disengaged from the driving ratchet, the lever 112 has been forced sufficiently downwards, so that the nose 97 of the lever 98 will be engaged 65 with the nose 96 of the lever 92. The lever 98 will thus be blocked in its initial position by the lever 92, and the pawl 53 cannot engage with another tooth of the driving ratchet 51, when, after the disengagement, the pawl 53 is swung 70 to the left by the spring 118.

The printing of the type "Z" indicated by the perforations 9 and 6 in the column has thus been effected. It will be now supposed that the column of the card contains the perforations 8 and 6 75

indicating the letter "R." As previously described, the shaft 69 rotates in synchronism with the passing of the card in front of the card-reading device. The Fig. 11 shows the position of sector 63 when the perforation 9 passes the reading device 21. When the perforation 8 passes the reading device, the shaft 69 will have turned a number of degrees corresponding to the advance of the card in the direction of the arrow, the roller 66 will have moved a corresponding distance towards the center of the shaft 69, and the sector 63, pulled by the spring 62 will have such a position in this moment that, when the magnet 38 will be energized by the circuit established through the perforation 8, the lever 85 with its nose 87 will engage the second tooth indicated by 8 on the sector 63 arresting this latter and the pushing lever in the corresponding position. Said position is such that, when the perforation 6 as previously described establishes a second circuit and the pawl 53 engages the tooth 6 of the ratchet 51, it will be the step 8 and not the step 9 on the sector 55 that will engage with the extremity 84 of the pushing lever 70. The sector will swing less before it strikes the pushing lever, and the typehammer will be swung at an earlier moment in the cycle than previously described. A movement of one step of the sector 55 corresponds to an angular movement of the ratchet 151 equal to the fourth of the angle between two adjacent teeth of the ratchet. Because every ratchet tooth corresponds to 4 types on the circumference of the type-carrier, a movement of one step of the sector 55 corresponds to a movement of the type-carrier equal to the distance between two adjacent types measured on the circumference of the type-carrier. Thus the type lever will now hit the paper when the type adjacent and foregoing to the type "Z" passes the printing position. This is the type "R" that thus will be printed.

In the same manner the perforations 7 and 6 in one column of the card will print the type foregoing to the type R, that is the type H. The perforation 1 will establish the circuit for the magnet 38, at the moment when the nose 87 may engage the tooth 7 on the sector 63. The pushing lever will be arrested in such a position that the extremity 84 will engage with the step 7 of the sector 55 when this is swung by the ratchet. If there is no selection perforation, but only the perforation 6 in the column, this perforation will establish the circuit for the magnet 38, and the pawl 53 will engage with the tooth 6 on the ratchet exactly as previously described. The lever 85 will be released in the same moment as the pawl 53. The roller 66 is, in this moment, on the concentric part of the circumference of the shaft 69, and the pushing lever has taken the position shown Fig. 1. In this position the pushing lever will at once engage with the step 6 on the sector 55 when this is moved by the pawl 53 and the ratchet 51, as shown in Fig. 1. The type foregoing to the type H will be printed, this is the type 5.

When the pawl 53 thus engages the tooth 6 on the ratchet 51 one of four different types Z, R, H, 6 may be printed. The respective position of the pushing lever 70 determines which of these types shall be printed, the actual position of the lever varying and being controlled in accordance with the presence on the card of either one of the perforations 9, 8, or 7, or the absence thereof respectively. If there is a single perforation 5 in the column of the card, the ratchet will fur-

ther have advanced a distance equal to the distance between two teeth on the circumference of the ratchet, that is the pawl 53 will now engage with the tooth 5. Accordingly the type-carrier has turned a distance corresponding to 4 5 types on the circumference thereof, and will, as also type 5, be in printing position when the hammer strikes the paper. According to the presence of a selection perforation 9, 8, 7, or the absence of such perforation, the perforation 5 10 will effect the printing of the types Y, Q, G or 5 respectively. A perforation 4 in the same manner will effect the printing X, P, F or 4 and so on. The perforation 11 will effect the printing of the types S, J, A or of a sign. The types 9, 8 15 and 7 may be printed when indicated in the column by the two perforations 9 and 12, 8 and 12 or 7 and 12. The ciphers 9, 8 and 7 may also be indicated by one single perforation in the column as shown Fig. 12. To effect the printing in this 20 case, a device may be employed which automatically energizes the magnet 38 when the tooth 12 on the ratchet 51 passes the pawl 53, and the lever 85 previously has been released by one of the perforations 9, 8 or 7. For this purpose, the lever 85 is provided with a projection 160 which is engaged with one of the blades of the contact 161 in such a manner that the contact is open when the lever 85 is in the position shown Fig. 1, but closed when the lever is released by the magnet 38 as shown in Fig. 9. Another contact 162, Fig. 10 is closed by a cam 163 fixed on the shaft 1, every time the tooth 12 of the ratchet passes the pawl 53. If a perforation 9 in a column of a card has energized 35 the magnet 38 and released the lever 85 so that the contact 161 is closed and said perforation 9 is not followed by another perforation in the same column, when the tooth 12 of the ratchet passes the pawl 53 and the cam 163 closes the 40 contact 162, the following circuit is established— Fig. 10: battery 34, contact 39, contact 31, contact 161, contact 162, magnet 38 and back to the battery. The magnet 38 will be energized, the lever 98 released, the pawl 53 will mesh with the 45 tooth 12 on the ratchet, and the cipher 9 corresponding to the perforation 9 will be printed, just as if the column had contained the two perforations 9 and 12. Thus when the pawl 53 meshes with the tooth 12 on the ratchet, one of the types 50 9, 8, or 7 will be printed, depending on the position of the sector 63.

Instead of the contact 161, a mechanical device may evidently be controlled by the lever 85 in such a way that, when the lever 85 has previously 55 been released, a cam operated means 42 actuates the armature 105 and releases the lever 98.

Fig. 1 shows the position of the different levers at the moment when a perforation 6 is going to make contact with the brush 21, and no foregoing perforation in the same card has actuated the selection means. When the magnet now is energized, the pawl 53 will mesh with the tooth 6 of the ratchet, and the cipher 6 will be printed.

It is supposed in the preceding description 65 that the shaft 6 is integral with the type-carrier 7.

The device just described will work in the same manner if the type-carrier comprises individual typewheels for each circumferential column of the drum, each wheel being fixed in such a way 70 to the shaft 6 that when the hammer strikes the paper, the wheel may be arrested a short moment, while the shaft continues to turn, as shown Fig. 13. When the typehammer 52 strikes the paper 152 and pushes it and the ribbon 157 against 75

the typewheel 170, the friction between the hammer and the rotating wheel will tend to stop the wheel. This is possible owing to the spring 171 which at one end is fixed to the typewheel and at the other end to a pin 172 integral with the shaft 6. Normally the spring 171 keeps the wheel in a determined position, by pulling the wheel with its edge 173 against the pin 172. When the hammer strikes the wheel, the wheel may stop until the hammer springs back, whereafter the spring 171 restores the wheel to its normal position.

Figs. 14, 15 and 16 show another arrangement of the types on the typedrum. Each type 174 is fixed to a spring blade 175 which is fixed to a disc 176 common for a circumferential column rigidly fixed to the shaft 6. Between each circumferential column of types is mounted vertical to the shaft 6 and rigidly fixed to the disc 176, a plate 177 on which is riveted a series of flat pins 178, one pin 178 for each type. The spring blade 175 is fixed in such a way to the disc 176, that the spring blade pushes against the pin 178. When now the hammer strikes the type 174, the spring blade 175 permits the type 174 to remain immobilized a little moment, while the disc 176 and the plate 177 continue to turn with the shaft 6. When the hammer springs back, the spring blade 175 will again push against the pin 178 and bring back the type to its normal position relatively to the plate 177.

In the preceding description, it is supposed that the type-carrier is rotated constantly in synchronism with the shaft 1 and in synchronism with the passage of the cards in front of the card reading device. The cards generally succeed each other in a certain distance, as shown Fig. 10 and the interval between the cards corresponds to a part of the space 180, Figs. 1 and 4 of the circumference of the type-carrier where no types will be placed. Another part of this space corresponds to the part of the cycle in which the group is being selected. When this space on the type-carrier passes the printing position, no types can be printed, and the movement of the drum is lost. It is possible to avoid this lost movement, when the gear drive between the shaft 1 and 6 instead of being realised as previously described and shown Figs. 1 and 4, is realised as shown in Figs. 2 and 3. Instead of wheel 2, another wheel 181 is fixed to the shaft 1. This wheel 181 has a number of teeth cut off, the number of teeth remaining being equal to the number of teeth of the wheels 184 and 185. The wheel 185 is fixed to the type-carrier 1 which has a smaller diameter than shown on Figs. 1 and 4, and the types are spaced all round the circumference. To the wheel 181 is fixed a cam 182 which engages with a hollow-cam 183 fixed to the wheel 184. The wheel 181 is turning constantly with the shaft 1, but the type-carrier, owing to the teeth cut off the wheel 181 and to the cams 183-182, will be arrested when a type 186, Fig. 4, corresponding to the last perforation of a card has been printed, and until the following card has advanced so far that the perforation corresponding to the type 187, Fig. 4 is under the reading device. The shaft 1 and the shaft of the card reading device will thus rotate continuously while the type-carrier is stopped in the interval between two cards, and during the time when the group selection is executed.

The printing device described may also print the numbers indicated on a totalizer. This may be done automatically, whereby the stopping of the card feeding device and the set in action of

the total printing operation may be controlled by the cards in known manner. To avoid unnecessary schemes and explanations, it will be here described how a "grand total" may be printed, whereby the printing operation is set in action 5 manually.

The totalizers may be of any known construction. In the Fig. 17 is shown a known totalizer. The main shaft 1 of the printing device forms the main shaft 1 of the totalizer T, Figs. 5 and 17. 10 On this shaft is fixed a toothed-wheel 200 with 9 teeth in such a position that when the perforation 9 of a card is in front of the reading brush 27, Fig. 10, the wheel 200 takes the position shown Fig. 17 relatively to the wheel 201. The 15 perforation establishes the following circuit— Fig. 10: Battery 34, contact 39, card contact 37, contact plate 35, perforation of the card, brush 27, magnet 203 and back to the battery. The magnet 203 will therefore be energized in 20 timed relation to the value of the perforation, and in known manner actuate the totalizer in such a way that the totalizer wheel 204, Fig. 17 is turned a number of teeth corresponding to the value of the perforation. 25

When all the cards have passed the card reading device the number indicated on the wheel should be printed. In mesh with each totalizer wheel 204 is a wheel 205 which further meshes with a wheel 206 loosely mounted on a stationary spindle 207. To each wheel 206 is fixed an arm 208 of insulating material, provided with two contacts 209 and 210, electrically connected with each other. Adjacent each wheel is placed a plate 211 of insulating material, provided with a contact ring 212 and 10 contact plugs 213, numbered from 0 to 9, in such position that the contact 210 on the arm 208 always makes contact with the contact ring 212, and the contact 209 makes contact with one of the plugs 213 for every 30 position that the totalizer wheel may take. It is understood that when the totalizer wheel indicates 9, the contact 209 makes contact with the plug 9, when the wheel indicates 8, the contact 209 makes contact with the plug 8 and so on. 40 The ring 212 is electrically connected to the inferior blade of contact 245. The contact plugs 213 are connected to the brushes 218 which are in contact with the commutator 219. This commutator is fixed on the shaft 1 and rotates in 50 synchronism with the typedrum 1. It comprises a cylinder of insulating material and has spaced on the circumference spots 220 of conducting material which are in electrical connection with each other and with the slip ring 55 221, which cooperates with the brush 222. The spots 220 are numbered from 9 to 0 and so placed on the insulated cylinder that the spot 9 will make contact with the corresponding brush 218 when the type 9 on the typedrum passes the 60 printing operating position. The spot 8 makes contact with the corresponding brush when the type 8 passes the printing operation position, and so on. The brush 222 is connected with the battery. When the shaft 1 is rotating, the commutator 219 will initiate electrical impulses, corresponding to the impulses initiated by the perforations of a card passing the card reading device. The slip ring 223 connects the two brushes 224 and 225 during that part of the cycle in which 70 the types 9 to 0 on the typedrum pass the printing operating position. The conducting spot 226 connects the two brushes 227 and 228 just an instant before the type 9 passes the printing operating position. The key 229 comprises a vertical 75

rod 230 of insulating material lodged in the frame 231. A link 232 connects the lower extremity of the rod to the armature 233 of a magnet 234 fixed to the plate 235 integral with the frame. A bar 236 fixed to the frame limits the movement of the armature. A spring 238 fixed to the rod 230 and at its other end to the plate 239 fixed to the frame, pulls the armature 233 against the bar 236. Another spring 240 fixed to the rod 230 10 pulls the rod upwards so that the projection 241 of the rod pushes against the frame 231. The rod 230 is further provided with a projection 241 so formed that when the key 229 is pushed downwards, the projection 241 will engage underneath the lower blade of contact 242. When the key is released and the rod pulled upwards by the spring 240, the projection 241 will close the contact 242. In shunt with the magnet 234 is a magnet 243 which, when energized, closes the two contacts 244 and 245.

When a grand total is to be printed, the key 229 is pushed downwards and released, whereby the contact 242 will be closed. Just before the type 9 on the typedrum passes the printing operating position, the spot 226 on the commutator will connect the two brushes 227 and 228, and establish the following circuit: Battery 34, brush 228, spot 226, brush 227, contact 242, magnet 234, brush 225, slip ring 223, brush 224, and back to the battery. The magnet 234 will be energized and the armature 233 moved against the magnet, whereby the rod 230 will be moved in the same direction, so that the projection 241 comes out of engagement with the lower blade of the contact 242, and the contact 242 is opened. Simultaneously with the establishing of the circuit which energizes the magnet 234, the following circuit is established: Battery 34, brush 228, spot 226, brush 227, contact 242, magnet 243, brush 225, slip ring 223, brush 224 and back to the battery. The magnet 243 will be energized and the two contacts 244 and 245 will be closed. The contact 244 will maintain the magnet 243 energized until the slip ring 223 cuts off the circuit, when all the types from 9 to 0 on the typedrum have passed the printing operating position, by the following circuit: Battery 34, contact 244, magnet 243, brush 225, slip ring 223, brush 224, and back to the battery. The contact 245 prepares the establishing of the circuit which will energize the printing magnet, when the type to be printed passes the printing operating position. Said circuit is finally established by the commutator 219 when the spot 220 corresponding to the cipher indicated on the totalizer wheel, makes contact with one of the brushes 218. Supposing the totalizer wheel indicates 5, the arm 208 will have such a position that the contact 209 makes contact with the number 5 of the contact plugs 213.

When number 5 of the spots 220 makes contact with the corresponding brush 218, the following circuit is established: Battery 34, brush 222, spot number 5, brush 218, line 5, contact plug 213, number 5, contact 210, contact 209, contact ring 212, line 250, contact 245, magnet 38 and back to the battery. As already mentioned, the spot 5 makes contact with the brush when the type 5 on the type-carrier passes the printing operating position. When the magnet 38 is energized in this moment, the type 5 will be printed in the same manner as described for a perforation 5 on a card.

While I have described what I deem to be practical and efficient embodiments of my invention, it should be well understood that I do not wish

to be limited thereto as there might be changes made in the arrangement, disposition and form of the parts without departing from the principle of my invention as comprehended within the scope of the appended claims.

What I claim is:

1. In an alphabetical printing device for record card controlled machines, a rotating type-carrier with types spaced about the circumference thereof and arranged in groups, a paper adjacent said type-carrier, a typehammer adapted to strike the paper against the type-carrier, analyzing means for reading the indications on the record card, card feeding means for feeding the cards past the analyzing means, a record card having one group indication for indicating the group to which a character belongs and one type indication to indicate a determined type within each group, selecting means controlled by the analysis of a group indication on a card and comprising a selecting member, means for positioning said selecting member in a different and determined position in regard of each different group indication read on the card, a toothed driving element, a toothed clutch member adapted to engage said toothed driving element, means including said selecting member and said clutch member for transmitting movement from the driving element to the hammer to strike the type-carrier, and means adapted to move one single tooth on the toothed driving element past a tooth on the toothed clutch member for each possible reading of a type indication or group indication on a card.

2. In an alphabetical printing device for record card controlled machines, a rotating type-carrier with types spaced about the circumference thereof and arranged in groups, a paper adjacent said type-carrier, a typehammer adapted to strike the paper against the type-carrier, a clutch member, a continuously moving driving element adapted to engage said clutch member, means permitting the driving element to displace the clutch member when the clutch member and the driving element are engaged, means for moving said hammer in relation to the type-carrier when said clutch member is displaced, means for reading two differently located indications on a card in movement during one single revolution of the type carrier means for feeding one card past said reading means for every revolution of the type-carrier, means responsive to the reading of said two differently located indications on a card for controlling the starting time of the simultaneous movement of the clutch member and the typehammer to effect the printing of the selected type during the same revolution of the type carrier during which said card was moved past the reading means.

3. In an alphabetical printing device for record card controlled machines, a rotating type-carrier with types spaced about the circumference thereof and arranged in groups, a paper adjacent said type carrier, a hammer adjacent said type-carrier and adapted to strike the paper against the type-carrier to effect printing, analyzing means for reading the indications on the card, card feeding means for feeding the card past the analyzing means, a driving element, a clutch member adapted to engage the driving element, selecting means controlled by the analysis of an indication in the card and comprising a selecting member, means for positioning said selecting member in one of a predetermined number of positions, each position corresponding to the 75

analysis of an indication in the card, and means associated with said selecting member and adapted to control the lapse of time from the time the clutch member has been engaged with the 5 driving element until the hammer hits the type-carrier comprising means for imparting the movement of the clutch member when said clutch member is engaged with said element to said selecting member, and means for striking the hammer 10 against the type-carrier during said movement of said selecting member.

4. In an alphabetical printing device for record card controlled machines, a rotating type-carrier with types spaced about the circumference thereof and arranged in groups, a paper adjacent said type-carrier, a typehammer adapted to strike the paper against the type-carrier, analyzing means for reading the indications on a record card, selecting means controlled by said analyzing means 15 and operated upon the analysis reading of an indication in a card means for continuously feeding the card past said analyzing means during said analysis reading of the card, further selecting means operated upon an analysis of a second 20 indication in the card when the card is in a position different from the position in which it was when said first indication was analyzed, a toothed driving element, said further selecting means comprising a toothed clutch member adapted to be engaged with said driving element, means for moving the hammer against the type-carrier when said clutch member is moved by said driving element and means for moving one single tooth of the toothed driving element past one 25 tooth of the toothed clutch member for each 30 analysis of an indication in a card.

5. In an alphabetical printing device for record card controlled machines, a type-carrier with types spaced about the circumference thereof and arranged in groups, a paper adjacent said type-carrier, a typehammer adapted to strike the paper against the type-carrier, a toothed driving element, a card analyzing device for reading the indications thereon, a magnet controlled by said 40 card analyzing device, selecting means controlled by said magnet adapted to select a predetermined group of types, a second selecting means controlled by the same magnet adapted to select the type to be printed within the group selected by 45 said first selecting means, said second selecting means comprising a toothed clutch member adapted to be engaged with said driving element and to move the hammer against the type-carrier when said clutch member is engaged with said driving element, and means for continuously rotating the type-carrier during the operation of 50 said first and second selecting means.

6. In an alphabetical printing device for record card controlled machines, a rotating type-carrier with types spaced about the circumference thereof and arranged in groups, a paper adjacent said type-carrier, a typehammer adapted to strike the paper against the type-carrier, analyzing means for reading the indications on the record cards, card feeding means for continuously feeding the cards past the analyzing means, a record card having one group indication for indicating the group to which a character belongs and one type indication to indicate a determined type within each group, driving means, a clutch member adapted to be engaged with the driving means and when engaged therewith to be moved by said driving means, a selecting member adapted to be positioned in one of a determined number of 55 positions, each position corresponding to a group

indication on the card, means for controlling by a group indication on the card the positioning of said selecting member and by a type indication on the same card the engagement of said clutch member with said driving means, at a 5 moment determined only by said second type-indication, and means for transmitting the movement of the clutch member to the hammer so as to cause the hammer to strike the type-carrier, said means controlling in cooperation with 10 said selecting member the lapse of time from the moment the clutch member has been engaged with the driving means until the hammer strikes the type-carrier.

7. In an alphabetical printing device for record card controlled machines, a rotating type-carrier with types spaced about the circumference thereof and arranged in groups, a paper adjacent said type-carrier, a typehammer adapted to strike the paper against the type-carrier, card analyzing 15 means for reading the indications on the card, card feeding means for continuously feeding a card past the analyzing means, a driving element, a clutch member adapted to engage said driving element and to be moved by said driving 20 element when being so engaged, a selecting member adapted to be positioned in a determined number of positions, each position corresponding to a determined indication on the card and further adapted to transmit the movement of the 25 clutch member to the hammer whereby said movement of the hammer will be differently timed for each position of the selecting member, and means for controlling from one single card reading station, the starting time of simultaneous 30 movement of said hammer and said clutch member.

8. In an alphabetical printing device for record card controlled machines, a rotating type-carrier with types spaced about the circumference thereof and arranged in groups, a paper adjacent said type-carrier, a typehammer adapted to strike the paper against the type-carrier, card analyzing means for reading the indications on the card, card feeding means for continuously feeding a 40 card past the analyzing means, a driving element, a clutch member adapted to engage said driving element and to be moved by said driving element when being so engaged, a selecting member adapted to be positioned in a determined 45 number of positions, each position corresponding to a determined indication on the card and further adapted to transmit the movement of the clutch member to the hammer whereby said movement of the hammer will be differently timed for each position of the selecting member, and means for controlling by said analyzing means the starting time of simultaneous 50 movement of said hammer and said clutch member.

9. In an alphabetical printing device for record card controlled machines, a rotating type-carrier with types spaced about the circumference thereof and arranged in groups, a paper adjacent said type-carrier, a type-hammer adapted to strike the paper against the type-carrier, analyzing means for reading the indications on the record cards, card feeding means for continuously feeding the cards past the analyzing means, a record card having one group indication for indicating the 60 group to which a character belongs and one type indication to indicate a determined type within each group, a toothed driving element moved in synchronism with the movement of the card past said analyzing means, a clutch 65

- member adapted to engage said driving element and to transmit the movement of the driving element to the hammer during such engagement, whereby the hammer will strike the type-carrier,
5 a number of teeth on said driving element, such that one single tooth on said driving element passes the clutch member for each type indica-

tion on the card that passes the analyzing means, one single magnet responsive to the reading of a group indication and a type indication on the card and means for controlling the simultaneous movement of said clutch member and said hammer by said single magnet. 5

KNUT A. KNUTSEN.
